UNITED STATES PATENT OFFICE.

ROBERT Z. FARMER, OF BISBEE, ARIZONA.

MOTOR.

1,118,117.

Specification of Letters Patent. Patented Nov. 24, 1914.

Application filed September 4, 1914. Serial No. 860,262.

To all whom it may concern:

Be it known that I, ROBERT Z. FARMER, a citizen of the United States, residing at Bisbee, in the county of Cochise and State of Arizona, have invented certain new and useful Improvements in Motors, of which the following is a specification, reference being had to the accompanying drawings.

This invention relates to certain improvements in motors and has relation more particularly to a device of this general character wherein an expansive fluid is employed; and an object of the invention is to provide a device of this general character having novel and improved means whereby a rectilinear movement is converted into rotary motion.

It is also an object of my invention to provide a device of this general character having novel and improved means whereby the exhaust is employed to overcome a dead center.

Furthermore, it is an object of my invention to provide a device of this general character including a reciprocating piston coacting with a cam and having, in part, novel and improved means for controlling the supply and exhaust of the fluid; and having, in part, novel and improved means whereby the controlling means may be adjusted for determining the direction of rotation.

The invention consists in the details of construction and in the combination and arrangement of the several parts of my improved motor whereby certain important advantages are attained and the device is rendered simpler, less expensive and otherwise more convenient and advantageous for use, all as will be hereinafter more fully set forth.

The novel features of the invention will be carefully defined in the appended claims.

In order that my invention may be the better understood, I will now proceed to describe the same with reference to the accompanying drawings, wherein—

Figure 1 is a side elevational view, with a part in section, of a motor constructed in accordance with an embodiment of my invention; Fig. 2 is a horizontal sectional view taken substantially on the line 2—2 of Fig. 1; Fig. 3 is a sectional view taken substantially on the line 3—3 of Fig. 2, with the rotor in a differing position; Fig. 4 is a sectional view taken substantially on the line 4—4 of Fig. 3, with the rotor omitted; Fig. 5 is a fragmentary elevational view of the

stator as illustrated in Fig. 4; Fig. 6 is a fragmentary sectional view illustrating a second bucket wheel herein embodied; Fig. 7 is a fragmentary view, partly in section and partly in elevation, illustrating one of the cams herein employed for controlling the valve mechanism; and Fig. 8 is a detail elevational view of the operating means for the boxings.

As disclosed in the accompanying drawings, 1 denotes a stator of suitable dimensions and provided with a supporting base or pedestal 2 whereby the same may be maintained in desired position. The stator, as herein embodied, is provided with the detachable end plates or heads 3 and with the continuous track-way 4 disposed on a predetermined curvature and preferably of the cam formation as is particularly illustrated in Fig. 3, and which arrangement of the track-way in practice has been found to result in a maximum of efficiency as the possibility of a dead center is substantially entirely eliminated.

Rotatably supported in the side plates or heads 3 of the stator, as herein set forth, and at a point eccentric to the axial center of the track-way 4, are the trunnions 5 oppositely directed from the cylinder 6 at the longitudinal center thereof, said cylinder and its trunnions constituting the rotor of my improved motor. The trunnions 5 project exteriorly of the stator a predetermined distance and are provided therethrough with the ports 7 which are in communication with the interior of the cylinder 6 adjacent the opposite extremities thereof, one port 7 being reversely directed relative to the second port and for which purpose the sides of the cylinders may be enlarged, as indicated at 8, without in any way affecting the balance.

Mounted for reciprocating movement within the cylinder 6 intermediate the delivery ends of the ports 7 is the piston 9 operatively engaged in any desired manner with the rod 10 projecting beyond the opposite extremities of the cylinder 6, the free extremities of said rod 10 being in contact with the continuous track-way 4, as is particularly illustrated in Fig. 2. In order to reduce to a minimum the possibility of any resultant friction, I find it of advantage to have operatively mounted in each extremity of the rod 10 the roller 11 which contacts directly with the track-way 4.

Each of the ports 7 serves, in the present

embodiment of my invention, for the purpose of supply and exhaust and the projected extremity of each of the trunnions 5 is inclosed within a boxing 12 mounted for 5 axial rotation relative to the trunnion 5 independently of the rotary movement of the trunnion proper, and such boxing is provided with a supply port 14 and an exhaust port 15 preferably in substantially opposite 10 relation and the flow through each of the ports 14 and 15 is under control of the valve 16 normally maintained in closed adjustment under the influence of the expandable member 17 in a manner which is believed to be self-evident.

As is believed to be clearly apparent to those skilled in the art to which my present invention appertains, it is necessary that the valves 16 be operated in unison but in 20 reverse directions and as herein embodied the requisite adjustment of the valves is accomplished through the medium of the reversely disposed cams 18 coacting with the stems 19 of the valves and by which arrangement, it will be readily perceived, especially as is illustrated in Fig. 2, that the exhaust valve 16 will be closed when the delivery valve is open and vice versa. The cams 18 serve as a timed means for controlling the 30 opening and closing of the respective valves 16, and it will be readily appreciated that by adjusting the time of operation of the cams 18, the direction of travel of the rotor may be determined. As herein set forth, 35 the independent axial movement of the boxing 12 permits of a ready reversal of the rotor, and in order that the necessary movement may be imparted to the boxing I have suitably secured thereto the lever 19 provided 40 with a conventional spring latch 20 coacting with the rack 21, herein disclosed as operatively supported by the base or pedestal 2. In my present disclosure, two boxings 12 are employed and in order that 45 the same may be axially rotated or rocked in unison, I find it of advantage to have the respective levers 19 suitably timed or connected, as indicated at 22 in Fig. 8. In view of this simultaneous operation of the respective levers 19, it will be appreciated that the latch 20 may be omitted in connection 50 with the second of the levers.

In order to prevent displacement of the boxings 12 from the trunnions 5, I find it of 55 advantage to employ in connection with each of the racks 21 a cross bar 23 overlying the forward face of the adjacent boxing 12 and provided with a suitable opening 24 through which the lug 25, produced at the 60 axial center of the forward face of the boxing, projects. This construction is believed to be fully illustrated in Figs. 1 and 2.

In communication with each of the supply ports 14 is a conduit 26 leading from a 65 suitable source of supply and having inter-

posed therein the controlling valves 27. As herein set forth, I have the supply conduits 26 leading from a common main 28 in which is also interposed a controlling valve 29. It is also to be observed that the portions 30 of the supply conduits in direct connection with the induction or supply ports 14 are flexible in order to afford no hindrance to the axial adjustment of the boxings 12.

While in practice I have found that a 75 motor constructed in accordance with an embodiment of my invention, as hereinbefore set forth, substantially reduces to a minimum the possibility of a dead center, I find it of advantage to employ additional 80 means to positively prevent such occurrence. As herein embodied, I suitably affix to each of the trunnions 5 a bucket wheel 31 disposed in reverse relation and delivering through the stator 1, as particularly illustrated at 32, at a predetermined point relative to each of the bucket wheels 31 is a conduit 33 leading from the exhaust conduit 34 common to both of the exhaust ports 15, and said conduit 33 has interposed therein 85 the controlling valve 35 whereby the discharge may be readily regulated in order to coact with the requisite bucket wheel 31, as depending upon the direction of rotation of the rotor. It is also to be observed that the end portions 36 of the conduit 34 directly in connection with the ports 15 are also 90 flexible in order to afford no obstruction to the axial adjustment of the boxings 12.

In order that the exhaust delivered upon 100 the respective wheels 31 may be readily delivered to the atmosphere, I provide at a proper point relative to each delivery point 32 a port 37 as is particularly illustrated in Fig. 1, and I also find it of advantage to 105 have each of the wheels 31 in close proximity to a head or side plate 3 so that a single segmental flange 38 may be employed for bridging the space between each of the points 32 and port 37 in order to properly 110 confine the exhaust.

While my motor, as herein embodied, is primarily intended to be operated by compressed air, I do not wish to be understood as limiting myself in this particular, as steam 115 or any other expansive force may be employed with equal facility, and if under requisite tension I have also found that water may be employed.

From the foregoing description, it is 120 thought to be obvious that a motor constructed in accordance with my invention is of an extremely simple and comparatively inexpensive nature and is particularly well adapted for use by reason of the convenience and facility with which it may be assembled, and it will also be obvious that my invention is susceptible of some change and modification without material departure 125 from the principles and spirit thereof and 130

for this reason I do not wish to be understood as limiting myself to the precise arrangement and formation of the several parts herein shown in carrying out my invention in practice.

I claim:

1. A motor of the character described comprising a continuous track-way of suitable curvature, a cylinder mounted for rotary movement, a piston within the cylinder, a rod for the piston projecting beyond the opposite extremities of the cylinder, said projected extremities of the rod being in contact with the track-way, means capable of alternate operation for admitting fluid within the cylinder at opposite sides of the piston, and means whereby the exhaust from within the cylinder is caused to impart rotation to the cylinder.

2. A device of the character described comprising a continuous track-way of predetermined curvature, a cylinder rotatably mounted relative to the track-way and provided with oppositely disposed trunnions, said trunnions being provided with ports disposed longitudinally thereof and in communication with the interior of the cylinder, a piston within the cylinder at a point intermediate the inner ends of the ports and having a rod projecting beyond opposite ends of the cylinder, the projected extremities of the rod being in contact with the track-way, a boxing rotatably engaged with each of the trunnions and capable of movement independently thereof, said boxing being provided with an inlet port and exhaust port, valves for controlling the inlet port and the exhaust port, cams carried by the trunnions coacting with the valves for operating the same in unison but in reverse relation, and means for imparting rotary movement to the boxing.

3. A device of the character described comprising a continuous track-way of predetermined curvature, a cylinder rotatably mounted relative to the track-way and provided with oppositely disposed trunnions, said trunnions being provided with ports disposed longitudinally thereof and in communication with the interior of the cylinder, a piston within the cylinder at a point intermediate the inner ends of the ports and having a rod projecting beyond opposite ends of the cylinder, the projected extremities of the rod being in contact with the track-way, a boxing rotatably engaged with each of the trunnions and capable of movement independently thereof, said boxing being provided with an inlet port and exhaust port, valves for controlling the inlet port and the exhaust port, means carried by the trunnion coacting with the valves for operating the same in unison but in reverse relation, and means for imparting rotary movement to the boxing.

4. A device of the character described comprising a continuous track-way of predetermined curvature, a cylinder rotatably mounted relative to the track-way and provided with oppositely disposed trunnions, said trunnions being provided with ports disposed longitudinally thereof and in communication with the interior of the cylinder, a piston within the cylinder at a point intermediate the inner ends of the ports and

having a rod projecting beyond opposite ends of the cylinder, the projected extremities of the rod being in contact with the track-way, a boxing rotatably engaged with each of the trunnions and capable of movement independently thereof, said boxing being provided with an inlet port and exhaust port, valves for controlling the inlet port and the exhaust port, cams carried by the trunnions coacting with the valves for operating the same in unison but in reverse relation, and means for imparting rotary movement to the boxing.

5. A device of the character described comprising a continuous track-way of predetermined curvature, a cylinder supported for rotary movement relative to the track-way, said cylinder being provided with oppositely directed trunnions, a piston within the cylinder, a rod projecting through the cylinder and operatively engaged with the piston, the extremities of the rod being in engagement with the track-way, the trunnions being provided with ports in communication with the opposite extremities of the cylinder, each of said ports serving as a means of supply and exhaust, and means for controlling the flow through the ports.

6. A device of the character described comprising a continuous track-way of predetermined curvature, a cylinder supported for rotary movement relative to the track-way, said cylinder being provided with oppositely directed trunnions, a piston within the cylinder, a rod projecting through the cylinder and operatively engaged with the piston, the extremities of the rod being in engagement with the track-way, the trunnions being provided with ports in communication with the opposite extremities of the cylinder, each of said ports serving as a means of supply and exhaust, means for controlling the flow through the ports, a bucket wheel fixed to one of the trunnions, and means for causing the exhaust from the cylinder to impact upon the bucket wheel.

In testimony whereof I hereunto affix my signature in the presence of two witnesses.

ROBERT Z. FARMER.
